UNITED STATES PATENT OFFICE.

DENIS F. HOGAN, OF ST. PAUL, MINNESOTA.

EXCAVATING-MACHINE.

1,003,458.

Specification of Letters Patent. Patented Sept. 19, 1911.

Application filed November 28, 1910. Serial No. 594,424.

To all whom it may concern:

Be it known that I, DENIS F. HOGAN, a citizen of the United States, residing at St. Paul, in the county of Ramsey and State of Minnesota, have invented certain new and useful Improvements in Excavating-Machines; and I do hereby declare the following to be a full, clear, and exact description of the invention, such as will enable others skilled in the art to which it appertains to make and use the same.

My invention has for its object to provide an improved excavating and loading machine adapted for general use but especially adapted for use in excavating and loading earth containing rock and minerals which cannot be readily handled by the ordinary excavating devices. The machine may be used in the digging of trenches, but is particularly designed for tearing down embankments and elevating the same to be loaded on cars, wagons or the like.

The invention, in its preferred form, is illustrated in the accompanying drawings, wherein like characters indicate like parts throughout the several views.

Referring to the drawings, Figure 1 is a view in side elevation, with some parts broken away, showing the improved machine; Fig. 2 is a plan view of the machine, with some parts broken away; Fig. 3 is a view in front elevation, with some parts broken away, showing the supporting frame and driving connections of a so-called embankment rake; Fig. 4 is a transverse section taken on the line $x^4 x^4$ of Fig. 1; Fig. 5 is a detail in vertical section taken approximately on the line $x^5 x^5$ of Fig. 2; Fig. 6 is a detail in vertical section, showing one of the angle iron slats of the elevating belt; Fig. 7 is a front elevation of the parts shown in Fig. 6 and showing also cam devices sectioned on the line $x^7 x^7$ of Fig. 5; Fig. 8 is a plan view with parts broken away, showing one of the long toothed slats of the elevating belt; Fig. 9 is a section on the line $x^9 x^9$ of Fig. 8; Fig. 10 is a plan view showing one of the short toothed slats of the elevating belt; and Fig. 11 is a section on the line $x^{11} x^{11}$ of Fig. 10.

The framework of the excavating machine is indicated as an entirety by the numeral 1 and it is mounted on front wheels 2 and rear wheels 3. The front wheels 2 are secured on an axle 4 journaled in bearing

brackets 5 rigidly secured to the base of the frame 1. The rear wheels 3 are the steering wheels of the machine, which may be arranged and operated in any suitable way but which, as shown, are loosely journaled on an axle 6 carried by a center bearing 7 that is centrally pivoted to a bolster 8 rigidly secured to the base of the frame 1.

For elevating the rock, mineral or earth, I employ an endless belt or conveyer which, in itself, involves novel feature of construction and which, as preferably constructed, includes a pair of heavy laterally spaced sprocket chains 9 and closely positioned transversely extended angle iron or steel slats 10. The ends of these angle slats 10 are riveted or otherwise rigidly secured to projecting lugs 11 formed on the chain links, and the said chains at their joints are provided with small anti-friction wheels or rollers 12.

The chains 9 run over lower sprockets 13 and upper sprockets 14. The lower sprockets 13 are secured to a transverse sprocket shaft 15 which, as shown, is journaled in boxes 16 adjustably mounted in bearing heads 17 rigidly secured to the lower end of parallel upper and lower angle iron guide rails 18 and 19, over the flanges of which the said chains are arranged to run with their wheels 12 engaged with the said flanges. The said guide rails 18 and 19 are inclined toward the front of the machine and are rigidly secured to the upright side portions of the main frame 1.

The upper sprockets 14 are rigidly secured to a sprocket shaft 20 journaled in suitable bearings 21 secured on the rear upper portion of the frame 1. The conveyer slats 10 are also preferably connected at their central portions to an endless sprocket chain 22 which is adapted to run over sprockets or traction wheels 23 and 24 carried, respectively, by the sprocket shafts 15 and 20. It also is desirable to have the intermediate chain 22 run over an inclined central rail 25, which is suitably secured to transverse portions of the main frame 1.

About every sixth conveyer slat 10 is provided with relatively long outwardly projecting laterally spaced teeth 26 preferably bolted and, hence, detachably secured to the outwardly extended flanges of the said angle slats. The intermediate, or otherwise stated, all of the other conveyer slats 10 are pro-

vided with relatively short teeth 27, preferably bolted and, hence, detachably secured to the outwardly extended flanges thereof. The purpose of these relatively long and short teeth on the conveyer slats will be made clear in the description of the operation.

For some classes of work, and especially for handling gumbo, mud or other sticky materials, slat cleaning devices are provided (see particularly Figs. 5 to 11, inclusive). These slat cleaning devices, as preferably arranged, are in the form of flat bars 28 having studs 29 that project through perforations in the bottom flanges of the slats 10. The studs 29 are preferably guided by sleeves 30 secured, at their outer ends, by threaded engagement or otherwise, to the bottom flanges of the said slats 10. The sleeves 30 are provided with longitudinally extended slots 31 (see Fig. 6), and the studs 29 are provided with diametrically projecting pins 32 that work in and project through said slots. Coiled springs 33, which surround the sleeves 30, react against the bottom flanges of the slats 10 and against washers 34 that are pressed against the pins 32. These springs 33 thus normally hold the cleaning bars 28 against the bottom flanges of the respective slats 10, so that they are out of the way while the slats are picking up the material to be elevated.

When the slats 10 reach approximately their uppermost position, the projecting ends of the pins 34 come into engagement with segmental cam plates 35 (see Figs. 5 and 7), which cam plates, as shown, have bifurcated hubs 36 rested upon the upper sprocket shaft 20. Said cam plates are also provided with projecting arms 37 shown as rigidly secured to one of the cross members 1^a of the main frame 1, to thereby hold said cam plate fixed against rotation. The upper surfaces of the cam plates 35 are eccentric to the axis of the shaft 20, so that the cleaning bars 28 will be gradually forced outward as they make their rear downward movement and will thus positively force from the slats any material which might otherwise tend to adhere thereto. When the slats pass the lower rear extremity of the cam plates 35, the springs 33 will force the cleaning plates back to their normal positions against the bottom flanges of the slats. For handling drier materials, such as gravel, rock or ore, these cleaning devices will not be required and, hence, may be removed from the slats.

For brushing up gravel, rock and similar material at the receiving end of the endless elevating belt, heavy wire brushes 38 are adapted to be applied to certain of the slats 10 as shown in Fig. 5. These brushes should be bolted or otherwise detachably secured to the slats to which they are applied and,

usually, but not necessarily, they will be applied to slats from which the long teeth 26 have been removed. These brushes will be found especially serviceable for cleaning up broken rock or similar material from a rock base or other solid bed.

For tearing down embankments and delivering the gravel, rock or other material to the lower receiving portion of the elevator belt, I provide a so-called embankment rake or down drag, which, as preferably constructed, comprises laterally spaced sprocket chains 39, transverse connecting slats 40 and a supporting frame 41. The sprocket chains 39 run over lower sprockets 42 and upper sprockets 43. The lower sprockets 42 are secured to a lower sprocket shaft 44 which, as shown, is journaled in bearing sleeves 45 rigidly secured in bearings 46 bolted or otherwise rigidly secured to the projecting ends of the lower side bars of the frame 1. The lower side portions of the frame 41 are pivoted on the bearing sleeves 45, as best shown in Fig. 3. The upper sprockets 43 are secured to an upper sprocket shaft 47 journaled in bearing boxes 48 that are adjustably mounted in the upper side portions of the pivoted frame 41. The front intermediate portions of the chains 39 are also arranged to run over an idle roller 49 journaled in suitable bearings 50 on the sides of the said frame 41. The slats 40 are preferably made of angle iron or steel and they are provided, on their outwardly extended flanges, with laterally spaced teeth 51.

The side portions of the pivoted rake frame 41 are pivoted to the front ends of a pair of links 52, the rear ends of which are pivotally connected to the frame of a small wheel truck 53, the wheels of which are arranged to run between the inwardly extended flanges of laterally spaced pairs of parallel inclined rails 54 rigidly secured to the sides of the main frame 1. This truck 53 carries a weight, preferably in the form of a tank 55, adapted to be filled to a greater or less extent with water or other liquid, to thereby vary the downward pressure on the truck and, hence, the forward pressure on the embankment rake or down drag. The truck 53 is connected to one end of a cable 56 which is passed over a guide sheave 57 on the upper portion of the frame 1 (see Fig. 1), and the lower end of which is attached to a windlass shaft or drum 58 mounted in suitable bearings on the frame 1 and provided with an operating crank 59 and adapted to be held, when desired, by a suitable pawl and ratchet device 60.

The machine described is preferably a traction rig and is provided with an explosive engine or other suitable form of motor having connections for driving the traction wheels to propel the vehicle when desired.

and, also, when desired, to drive the endless elevating belt and embankment rake, either while the machine is standing still or while it is being propelled slowly forward.

- 5 The explosive engine, which is indicated as an entirety by the numeral 61, is suitably secured on the bed of the frame 1 and is provided with a long transversely extended crank shaft 62 mounted in suitable bearings in the engine base and on the said main frame. At one end, the engine crank shaft 62 is provided with a sprocket 63 and, at its other end, it is provided with a loose sprocket 64 and with a driving clutch 65, which latter is arranged to rotate with the said shaft but is adapted to slide on the shaft into and out of engagement with a clutch formed on the hub of the said loose sprocket 64.
- 20 A sprocket chain 66 runs over the sprocket 63 of the engine crank shaft and over a larger sprocket 67 secured to a transverse line shaft 68 mounted in suitable bearings on the base of the machine frame 1. On the 25 intermediate portion of the line shaft 68 is a loose sprocket 69, a loose spur gear 70 and a double-ended clutch sleeve 71. The said clutch sleeve 71 is keyed to rotate with the line shaft 68 but is adapted to slide so as to 30 be engaged at will with clutch members formed on the hubs of the sprocket 69 and gear 70. A sprocket chain 72 runs over the loose sprocket 69 and over a larger sprocket 73 secured to the axle 4 to which the 35 traction wheels 2 are secured. The axle 4 also carries a second large sprocket 74. A sprocket chain 75 runs over this sprocket 74 and over a smaller sprocket 76 secured to a reversing counter-shaft 79 mounted in suitable 40 bearings in the sides of the frame 1, and provided with a spur gear 80 that meshes with the spur gear 70 of the line shaft 68. When the clutch 71 is engaged with the clutch of the sprocket 69, the machine will 45 be driven backward, but when the said clutch 71 is engaged with the clutch of the spur gear 70, the machine will be driven forward.

To drive the endless elevator or elevating belt, a sprocket chain 81 is run over the sprocket 64 and over a larger sprocket 82 on a countershaft 83 extending transversely of the machine and journaled in suitable bearings on the sides of the frame 1 in proper 55 position to pass the said shaft through the space between the rails 18 and 19. Adjacent to the sprocket 82, the counter-shaft 83 is provided with a smaller sprocket 84 and, at its other end, it is provided with a similar sprocket 85. A sprocket chain 86 runs over the sprocket 84 and over a larger sprocket 87 secured to one end of the upper sprocket shaft 20.

The lower sprocket shaft 44 of the embankment rake is provided at one end with

a spur gear 88 that meshes with a spur gear 89 journaled to a suitable bearing in the frame 1 and having a sprocket 90 secured to its hub. A sprocket chain 91 runs over the sprockets 85 and 90.

70 Whenever the clutch member 65 on the engine crank shaft is engaged with the clutch of the normally loose sprocket 64, the countershaft 83 will be rotated and through the connections described, both the endless 75 elevating belt and the embankment rake will be thrown into action.

Summary of operation.--The manner in which the traction rig may be driven forward and thereby moved from place to place or advanced for continuous action on an embankment, and also the manner in which the elevating belt and the embankment rake may be thrown into action whenever desired have already been stated. When the machine is moved with the receiving or lower portion of the elevating belt against the bottom of an embankment and is driven, the long teeth 26 make the initial cut and loosen up the embankment and the shorter teeth 27 continue or complete the tearing of the bank at its base and put the earth, rock or other material in condition for easy delivery onto the angle iron slats of the elevator. Preferably, the teeth 26 and 27 are 85 staggered transversely of the machine, so that the teeth of the adjacent slat do not travel the same paths. As the projecting flanges of the angle slats 10 are moved upward on the sprockets 13, they scrape up the 90 earth, rock or other material from the embankment and thus the multiplicity of trough-like compartments of the elevator are loaded with the material. The loading of the trough-like compartments of the elevator or elevating belt is further insured by the action of a so-called embankment rake, which continually loosens and rakes or scrapes downward the dirt from the embankment and forces the same onto the upwardly 95 moving receiving portion of the elevator. By 100 adjustments of the truck 53 on the rails 54, the embankment rake may be set in any desired position, either inclined backward or forward or in an upright position, and thus 105 it may be set for proper position on any kind of an embankment. Usually, it will be inclined forward. The pressure under which the embankment rake may be set to work against the embankment may be varied by varying the amount of water contained in the tank 55. Thus, when the cable 56 is given slack, the embankment rake will be automatically kept to its work. When, however, it is desired the embankment rake may 110 be pulled rearward or controlled in its forward movement, by manipulation of the cable 52, accomplished by rotation of the windlass crank 59.

The truck 53, which has both upper and 115

lower wheels, runs between the flanges of the upper and lower rails 54 much after the manner of a crosshead.

What I claim is:

5. 1. In an excavating machine, the combination with an inclined elevator, of an embankment rake adjustably mounted in the vicinity of the receiving portion of said elevator, and a weighted traveling presser device, independent of said rake, for holding the same to its work.
10. 2. In an excavating machine, the combination with an inclined elevator, of an embankment rake adjustably mounted in the vicinity of the receiving portion of said elevator, a weighted traveling presser device, independent of said rake, for holding the same to its work, and means for holding said presser device in different set positions.
15. 3. In an excavating machine, the combination with an inclined elevator, of an embankment rake adjustably mounted in the vicinity of the receiving portion of said elevator, and a weighted traveling presser device, independent of said rake, for yieldingly holding the same to its work.
20. 4. In an excavating machine, the combination with an inclined elevator, of an embankment rake adjustably mounted in the vicinity of the receiving portion of said elevator, and a variably weighted traveling presser device, independent of said rake, for yieldingly holding the same to its work.
25. 5. In an excavating machine, the combination with an elevator and means for driving the same, of an embankment rake mounted above the receiving portion of said elevator for adjustments into different angular positions, means for driving said rake, a cross head or traveler mounted to travel on inclined runways, and a connection between said cross head and said embankment rake for adjusting the same.
30. 6. In an excavating machine, the combination with an elevator, of an endless embankment rake having a supporting frame pivotally mounted above the receiving portion of said elevator, means for driving said rake, a cross head or traveler mounted to run on inclined runways, an adjustable weight carried by said cross head, and a connection between said cross head and the frame of said rake for imparting angular adjustments thereto.
35. 7. In an excavating machine, the combination with an elevator and means for driving the same, of an endless slat and belt embankment rake having a supporting frame pivotally mounted above the receiving portion of said elevator, means for driving said rake, a cross head or traveler mounted to run on inclined runways, a liquid containing tank carried by said cross head, and a connection between said cross head and the frame of said rake for adjusting the same.
40. 8. In an excavating machine, an endless inclined elevator belt and means for guiding and driving the same, the said belt being made up of endless chains and angle cross slats, the said slats having relatively long and relatively short teeth projecting from their outwardly extended flanges.
45. 9. In an excavating machine, an endless inclined elevator belt and means for guiding and driving the same, the said belt being made up of endless chains and angle cross slats, the outwardly extended flanges of some of the said cross slats having relatively long projecting teeth and the outwardly extended flanges of a larger number of said slats having relatively short projecting teeth, the said teeth being staggered transversely of the machine.
50. 10. In an excavating machine, the combination with an endless elevating belt having angle cross slats, of cleaning devices applied to the said cross slats, and means for pressing said cleaning devices outward to clean the slats when the latter reach predetermined positions.
55. 11. In an excavating machine, the combination with an endless elevating belt and means for guiding and driving the same, the said belt being made up of endless chains and angle cross slats, of slat cleaning bars having studs working through the bottom flanges of said slats, and cam devices operative on the said cleaning devices to force the same outward and clean said slats when the latter reach their discharging positions.
60. 12. In an excavating machine, the combination with an endless elevator belt and means for guiding and driving the same, the said belt having angle cross slats with projecting teeth on their outwardly extended flanges, of slat cleaning devices applied to said slats, and means for forcing said cleaning devices outward to clean said slats when the latter reach their discharging position.

In testimony whereof I affix my signature in presence of two witnesses.

DENIS F. HOGAN.
